(57) **CLAIM**

The ornamental design for a container with lid as shown and described.

DESCRIPTION

FIG. 1 is a perspective view of a container with lid.

FIG. 2 is a front elevation view of the container with lid.

FIG. 3 is a rear elevation view of the container with lid.

FIG. 4 is a left side elevation view of the container with lid.

FIG. 5 is a right side elevation view of the container with lid.

FIG. 6 is a top plan view of the container with lid.

FIG. 7 is a bottom plan view of the container with lid.

FIG. 8 is an exploded perspective view of the container with lid.

FIG. 9 is a perspective view of the lid of the container with lid.

FIG. 10 is a front elevation view of the lid of the container with lid.

FIG. 11 is a rear elevation view of the lid of the container with lid.

FIG. 12 is a left side elevation view of the lid of the container with lid.

FIG. 13 is a right side elevation view of the lid of the container with lid.

FIG. 14 is a top plan view of the lid of the container with lid.

FIG. 15 is a bottom plan view of the lid of the container with lid.

FIG. 16 is a perspective view of the container of the container with lid.

FIG. 17 is a front elevation view of the container of the container with lid.

FIG. 18 is a rear elevation view of the container of the container with lid.

FIG. 19 is a left side elevation view of the container of the container with lid.

FIG. 20 is a right side elevation view of the container of the container with lid.

FIG. 21 is a top plan view of the container of the container with lid; and,

(Continued)

FIG. 22 is a bottom plan view of the container of the container with lid.

The broken lines shown in the drawing figures are for illustrative purposes only and form no part of the claimed design.
